PERRY W. SULLIVAN, OF SOUTH BEND, INDIANA, ASSIGNOR TO THE STUDEBAKER CORPORATION, OF SOUTH BEND, INDIANA, A CORPORATION OF NEW JERSEY

DOOR LATCH

Application filed April 22, 1929. Serial No. 357,058.

This invention relates to door latch operating handles and particularly to means whereby when the lock mechanism forming a part of the handle is moved to a predetermined position rotation of the handle will not permit unauthorized opening of the door.

The principal object of this invention is to provide a rotatable latch operating handle having a hollow shell extending into the door in which is rotatably mounted a key-controlled cylindrical member having a projection at its inner end thereof detachably engageable with the latch operating spindle whereby when the cylindrical member is moved to one position rotation of the handle will permit the opening of the door and when the cylindrical member is moved to another position the rotation of the handle will not permit the opening of the door.

Another object is to provide a latch operating spindle rotatably mounted in the hollow shell forming a part of the operating handle, the spindle having a slot in its inner end adapted to receive a projection formed on an end of the key-controlled cylindrical member rotatably mounted in the hollow shell of the operating handle whereby the rotation of the handle will permit the opening of the door of which the latch mechanism forms a part.

A further object is to provide a rotatable latch operating handle having a hollow shell extending into the door in which is rotatably mounted a key-controlled cylindrical member having a projection at the inner end thereof detachably engageable in a slot formed in a latch operating spindle rotatably mounted in the hollow shell forming a part of the operating handle, the rotatable cylindrical member being provided with a pin riding in a slot formed in a cylindrical sleeve seated in the latch operating handle whereby the projection on the end thereof is guided into the slot formed in the latch operating spindle. The above being among the objects of the present invention the same consists of certain features and combination of parts to be hereinafter described and then claimed, having the above and other objects in view.

In the accompanying drawings which il-

lustrate a suitable embodiment of my present invention,

Figure 1 is a longitudinal sectional view showing the latch operating handle and the lock mechanism therefor, the lock mechanism being shown in position whereby rotation of the handle will not operate the latch mechanism, certain parts of the device being shown in full lines and other parts broken away to more clearly show the invention. 55

Figure 2 is a fragmentary longitudinal section similar to Figure 1, showing the lock mechanism in operative position whereby rotation of the handle will operate the latch mechanism to open the door. 65

Figure 3 is an enlarged transverse sectional view taken substantially on the line 3—3 of Figure 2.

Figure 4 is a transverse sectional view taken on the line 4—4 of Figure 2, showing the means to prevent longitudinal movement of the latch operating spindle relative to the door operating handle. 70

Figure 5 is a transverse sectional view taken on the line 5—5 of Figure 2. 75

Figure 6 is fragmentary perspective view, showing the slot formed in the end of the latch operating spindle.

Referring in detail to the drawings in which like numerals refer to like parts throughout the several views, I have shown for the purpose of illustration a section of a motor vehicle door comprising an edge face member 1 having its front edge covered with a sheet metal plate 2. The latch mechanism 3, a portion only of which is shown in Figure 1, is suitably secured to the rear face of the door structure. 80

The latch mechanism may be of any desired type and is actuated by means of the exterior handle 4 having a shank 5 provided with an opening 6 extending therethrough terminating in an enlarged opening 7 through the handle portion 4 for a purpose to be hereinafter described. The shank 5 of the handle 4 is inserted through an opening 8 in the face plate 2 and is retained against longitudinal movement relative to the door by means of the nut 9 threaded on the shank 5. 95

An escutcheon member comprising the hollow shells 10 and 10' surrounds the shank 5 exteriorly of the face plate 2, the members 10 and 10' being retained in operative position by the spring 11. The escutcheon member for securing the handle 4 against longitudinal movement relative to the door forms no part of my present invention, the same being illustrated in my co-pending application for Letters Patent, Serial No. 350,895, filed March 29, 1929, in which application the construction and operation of the escutcheon member are clearly illustrated, so that a further description of the same in this present case is believed to be unnecessary.

The latch 3 is operated by the spindle 12 terminating at one end in an enlarged cylindrical portion 13 adapted to be rotatably received in the opening 6 formed in the shank 5. The end 13 of the spindle 12 is provided with a recess 13' in which is seated a pin 14 secured in the shank 5 as is clearly shown in Figures 1 to 4 to prevent longitudinal movement of the spindle 12 relative to the door operating handle 4. In the inner end of the member 13 is formed a slot 15, the edges of the slot being rounded at 16 as is clearly shown in Figure 6 for a purpose to be hereinafter described.

A hollow sleeve 17 is pressed into the opening 7 formed in the handle 4, the opening through the sleeve 17 being substantially the same diameter as the opening 6 formed in the shank 5 to slidably receive the cylindrical lock member 18. A plurality of lock plungers 19 extend transversely of the members 17 and 18, the same being suitably received in slots 20 and 21 formed respectively in the members 18 and 17, the plungers 19 being moved into the positions shown in Figures 1 and 2 by means of the key 22. The hollow sleeve 17 has formed therein a slot 23 adapted to receive and guide the pin 24 secured on the cylindrical lock member 18 for longitudinal moving the member 18 from the position shown in Figure 1 to Figure 2, and vice versa. The lock member 18 is provided with a projection 25 at its inner end adapted to be received in the slot 15 formed in the end 13 of the spindle 12.

Referring to Figure 1, the key 22 may be inserted in the slot formed in the lock member 18 to move the lock plungers 19 out of engagement with the hollow shell 17 whereupon the lock member 18 may be rotated and in so doing the pin 24 is moved in the slot 23 formed in the member 17 which causes the member 18 to move longitudinally relative to the handle 4 whereby the projection 25 is caused to engage in the slot 15 formed in the member 12. As previously stated the edges of the slot 15 are rounded off at 16 to permit easy engagement of the projection 25 therein. When the lock member 18 has been rotated by the key 22 in the manner just previ-

ously described the same will assume the position shown in Figure 2. In this position the lock plungers 19 will engage in the sleeve 17 whereby the handle 4, sleeve 17 and rotatable lock member 18 are secured together and rotation of the handle 4 will cause rotation of the spindle 12 to thus operate the latch 3 to permit the opening of the door.

Referring to Figure 2, the key 22 may then be inserted in the slot formed in the cylindrical lock member 18 which will move the plungers 19 from the position shown whereupon rotation of the key 22 will withdraw the projection 25 on the member 18 from the slot 15 formed in the member 13, the lock member 18 being guided to its reseated position by the pin 24 riding in the slot 23 so that the cylindrical lock member 18 will assume the position shown in Figure 1. When in this position the projection 25 is disengaged from the slot 15 so that rotation of the handle 4 will not rotate the spindle 11 to affect the latch mechanism 3. In other words, when the mechanism is shown as in Figure 1, the handle 4 may be rotated at will without operating to unlatch the door to permit opening the same by unauthorized persons.

It will thus be seen that I have provided a simple and efficient lock structure in a door operating handle effective to unlatch the door when in one position and which will prevent the unlatching of the door when in another position, and while I have shown one embodiment of my invention, it is understood that formal changes can be made therein without departing from the spirit and substance of my invention the scope of which is commensurate with the appended claims.

What I claim is:

1. In combination with a door structure having an opening in the side face thereof and a latch mechanism mounted thereon, a rotatable latch operating handle having a hollow shank extending into said opening, a latch operating spindle having one end mounted in said shank and its opposite end engageable with said latch mechanism, a key-controlled lock member mounted in said handle, and means for rotatably and slidably moving said lock member into engagement with said spindle whereby rotation of said handle will permit operation of said latch mechanism.

2. In combination with a door structure having an opening in the side face thereof and a latch mechanism mounted thereon, a rotatable latch operating handle having a hollow shank extending into said opening, a latch operating spindle having a slot formed in its inner end face mounted in said hollow shank, a key-controlled cylindrical member having a projection extending from its inner end face mounted in said handle, a sleeve having a slot therein surrounding said key-controlled cylindrical member, a pin ex-

tending from the cylindrical member riding in said slot, and means permitting said pin to slidably move in the slot formed in said sleeve whereby said key-controlled cylindrical member is caused to move longitudinally relative to said handle and said projection thereon is caused to engage in the slot formed in said spindle whereupon rotation of said handle will cause operation of said latch mechanism.

3. In combination with a door structure having an opening in the side face thereof and a latch mechanism mounted thereon, a rotatable latch operating handle having a portion extending into said opening, a latch operating spindle operatively engaging with said handle, a hollow sleeve having a slot formed therein positioned in said handle, and a key-controlled lock member having a projection thereon guided by said slot movable to engage said latch operating spindle to cause operation of said latch mechanism.

4. In combination with a door structure having an opening in the side face thereof and a latch mechanism mounted thereon, a rotatable latch operating handle extending into said opening, a latch operating spindle operatively engageable with said handle, a hollow sleeve having a slot therein mounted in said handle, a lock member having a projection on the side face thereof engageable in said slot, and means permitting said lock member to be rotated relative to said handle whereby said pin is caused to move in said slot and cause said lock member to engage with said spindle whereupon rotation of said handle will cause operation of said latch mechanism.

Signed by me at South Bend, Indiana this 40 18th day of April, 1929.

PERRY W. SULLIVAN.
